Application December 30, 1947, Serial No. 143,449

Term of patent 14 years

(Cl. D3—17)

To all whom it may concern:

Be it known that I, Sylvan Pleet, a citizen of the United States, residing in the city of Baltimore and State of Maryland, have invented a new, original, and ornamental Design for Trousers, of which the following is a specification, reference being had to the accompanying drawings, forming part thereof.

Figure 1 is a front view of a pair of trousers showing my new design, and

Figure 2 is a side view thereof, the opposite side being similar to the side shown.

The characteristic features of my design reside in the combination on the trousers disclosed of the plain appearing top portion having no visible waistband with pleats extending to the top edge of same in association with a tunnel underneath the pleated portion for a belt and a pair of slash pockets which are placed forward of the side seams, all as shown.

I claim:

The ornamental design for trousers, as shown and described.

SYLVAN PLEET.
